US0D1058360S

(12) **United States Design Patent** (10) **Patent No.:** **US D1,058,360 S**
(45) **Date of Patent:** **** Jan. 21, 2025**

(54) **RING AND GUSSET COUPLING**

(71) Applicant: **Victaulic Company**, Easton, PA (US)

(72) Inventors: **Michael Fleck**, Easton, PA (US); **Scott D. Madara**, Nazareth, PA (US); **Matthew A. Bowman**, Palmer, PA (US)

(73) Assignee: **VICTAULIC COMPANY**, Easton, PA (US)

(**) Term: **15 Years**

(21) Appl. No.: **29/748,345**

(22) Filed: **Aug. 28, 2020**

Related U.S. Application Data

(62) Division of application No. 29/681,871, filed on Feb. 28, 2019, now Pat. No. Des. 897,195.

CLAIM

The ornamental design for a ring and gusset coupling as shown and described.

DESCRIPTION

FIG. 1 is an isometric view of our design for a ring and gusset coupling;

FIG. 2 is a left side view thereof, the right side view being a mirror image thereof;

FIG. 3 is a front view thereof;

FIG. 4 is a rear view thereof;

FIG. 5 is a top view thereof; and,

FIG. 6 is a bottom view thereof.

The broken lines depict portions of the ring and gusset coupling that form no part of the claimed design.
